HARRY BONAT, OF NEW YORK, N. Y.

METHOD AND APPARATUS FOR WAVING HAIR

Application filed July 17, 1929. Serial No. 378,880.

This invention relates to permanent waving of hair and particularly to improvements in the so-called croquinole waving method and apparatus therefor.

5 The croquinole method of waving hair as heretofore practised consists in clamping a flattened lock or strand of the hair about three inches in width adjacent the scalp, winding the hair from the free ends upon 10 a metal spindle until the hair is under tension, applying a pad moistened with a suitable lotion to the hair, and then subjecting the pad and the hair enclosed therein to heat for a sufficient period to fix the curl. Owing 15 to the rounded contour of the head, and the necessity for employing a straight spindle for winding, it is apparent that the curl will commence at varying distances from the roots of the hair and consequently the resulting wave does not lie uniformly and is 20 not, therefore, satisfactory.

It is the object of the present invention to avoid the difficulty heretofore experienced in producing a satisfactory wave by the croquinole method and also to afford improvements 25 in the apparatus employed in carrying out the method whereby the operation is facilitated to produce a wave having the desired characteristics and appearance.

30 I have discovered that by treating a strand of hair not exceeding one and a half inches in width it is possible to clamp the hair more closely adjacent to the scalp and to produce, therefore, a more uniform and satisfactory 35 wave. In carrying out the method, I employ, instead of the usual clamps which are commonly about three inches in length, an improved clamp which is much shorter and is designed to secure a flattened strand of 40 the hair approximately one inch and not exceeding one and a half inches in width. The clamp may be disposed so close to the scalp that it conforms practically to the curvature of the head, that is to say, the distance between 45 the roots of the hairs and the commencement of the wave is substantially uniform when the operation is completed.

In carrying out the invention, I prefer to employ an improved clamp to grip the hair firmly adjacent the scalp. The clamp includes

arms pivoted to provide a jaw with grooves on the inner face of each arm. I provide a resilient member in one of the grooves consisting preferably of a piece of rubber tubing which is mounted on a rod or coiled 55 wire. The hair is disposed between the rubber tubing and the groove on the opposite side of the jaw. The clamp is then locked by a suitable device so that the hair is gripped firmly and cannot be pulled at the scalp when 60 it is wound tightly on the spindle.

The spindle comprises a metal rod preferably of smaller diameter at the middle than at the ends, with a locking finger which is adapted to hold the ends of the strand of hair while the strand is being wound on the spindle. The spindle is supported in suitable lugs on the clamp, and means is provided to prevent unwinding of the hair after 65 it has been wound on the spindle.

70 After the hair has been wound on the spindle, a pad which has been moistened with a suitable lotion, such as is commonly employed in the art, is disposed about the spindle, and the clamp carrying the spindle and pad is 75 enclosed within a suitable housing which is provided with means for heating, preferably an electrical heating element which is connected to a suitable source of current. Thus 80 heat is supplied to the hair through the overlying pad, and the heat is continued until the wave has been set. The hair is then released from the spindle and clamp. It will be understood that in the operation of the method a plurality of strands of hair are wound 85 upon a number of spindles held in clamps which are arranged upon the head in a manner such as to produce the desired wave. Heat is applied simultaneously to all of the strands, and the waving may be completed in one or 90 more operations as desired.

The invention will be understood more readily by reference to the following specification and accompanying drawings, in 95 which

Fig. 1 is a plan view of the clamp;

Fig. 2 is a similar view of the clamp showing the jaw open;

Fig. 3 is a side elevation of the clamp; 100

- Fig. 4 is an enlarged sectional view of the clamp with the spindle and heater;
- Fig. 5 is an enlarged sectional view of the clamp and spindle;
- 5 Fig. 6 is a section on the line 6—6 of Fig. 5;
- Fig. 7 is a section on the line 7—7 of Fig. 5; and
- Fig. 8 is a sectional view of a modified form of the resilient member in the clamp.
- 10 Referring to the drawings, 5 and 6 indicate the two arms of the clamp which may be made of any suitable metal, backed, preferably, with hard rubber, one of the arms being rigidly connected to a bracket 7, while
- 15 the other is pivoted at 8 thereto. Felt pads 9 are secured to the rear faces of the arms and are adapted to be disposed adjacent the scalp.
- Grooves 10 are provided on the inner faces
- 20 of the arms 5 and 6, and in one of these grooves a resilient member such as a piece of rubber tubing 11 is supported on a rod 12. One end of this rod is secured by a pin 13 in a slot 14 in the bracket 7, the other end
- 25 being free. In place of the rod, a coiled wire 12' (Fig. 8) may be employed to support the rubber tubing.
- The clamp is locked by an arm 15 pivotally secured to the free end of the arm 5 and
- 30 adapted to engage slots 16 and 17 in the arms 5 and 6. An eccentric lever 18 is pivoted to the arm 15 and engages the arm 6 to force the arms closely together and thus to grip the hair.
- 35 When the hair has been clamped adjacent the scalp, a spindle 20 having a pivoted finger 21 is supported in the bracket 7 and in a similar bracket 22 at the opposite end of the clamp. Ratchet teeth 23 on the spindle
- 40 are adapted to engage a pawl 24 so that the spindle can be rotated only in one direction. A pin 19 with a squared end engaging the bracket 22 is rotatably mounted in a bushing 19' which is forced into the end of the spindle 20. The bushing 19' has internal ratchet teeth 20' which are engaged by a spring pawl 21' secured to the pin 19. Thus the spindle 20 may be rotated relatively to the pin 19 in one direction. The ratchet teeth 19' and 23 afford a double lock to prevent reverse rotation of the spindle 20.
- The ends of the hair forming the strand are wound about the spindle and held by the finger 21. Thereupon the spindle is rotated by means of a knurled head 25 until the strand of hair is wound tightly thereon. The spindle is turned until the hair is stretched and is held under considerable tension. Thereupon a pad 26 is moistened with a suitable lotion and disposed about the hair on the spindle. The heating device is then disposed about the pad and spindle, and heat is applied to fix the wave.
- The heating device is well-known in the
- 45 art and need not be described in detail. It
- comprises two relatively moveable parts 27 which, when brought together, form a substantially cylindrical chamber. The heating elements 28 are disposed within the wall of this chamber and are adapted to be connected to any suitable source of current. The device is adapted to be held in closed position by a latch 29 which engages a pin 30 against the tension of springs 31. When the latch is released, the device opens under the tension of the springs and may be disposed over the hair and spindle and then closed by means of handles 32 provided for that purpose. When the heating is completed, the heating device is similarly released and removed.
- The method of waving as hereinbefore described depends upon the treatment of a lock or strand of hair not exceeding one and a half inches in width. As I have pointed out, the treatment of a wider strand produces an uneven wave because of the varying lengths of the straight portions of the hairs adjacent the scalp. By treating the relatively narrow strand the inequalities in the straight portions of the hair adjacent the scalp are minimized so that the wave more closely approaches a natural wave and consequently affords a more satisfactory result.
- While I have provided an improved clamp for use in practising the method, it is to be understood that any of the well-known devices adapted for this purpose may be utilized, provided that the strand of hair which is wound thereon does not exceed one and a half inches in width and is, preferably, somewhat narrower to avoid the difficulty which has been experienced heretofore in waving hair by the croquinole method.
- Various changes may be made in the details of the apparatus employed and in the procedure as described, without departing from the invention or sacrificing any of the advantages thereof.
- I claim:
1. In a device for permanently waving hair, a clamp having opposed relatively movable arms each provided with a groove, a rod supporting resilient means in one of the grooves, the resilient means being adapted to co-operate with the groove in the opposite arm to firmly grip the hair, and means for locking the arms in closed position.
- 110
1. In a device for permanently waving hair, a clamp having opposed relatively movable arms each provided with a groove, a rod supporting resilient means in one of the grooves, the resilient means being adapted to co-operate with the groove in the opposite arm to firmly grip the hair, and means for locking the arms in closed position.
- 115
2. In a device for permanently waving hair, a clamp having opposed relatively movable arms each provided with a groove, a rod supporting resilient means in one of the grooves, the resilient means being adapted to co-operate with the groove in the opposite arm to firmly grip the hair, means for locking the arms in closed position, a spindle co-operating with the clamp, and a double lock permitting rotation of the spindle only in one direction.
- 120
3. In a device for permanently waving
- 125

hair, a clamp having opposed relatively movable arms, each provided with a groove, a rod pivotally supported and carrying resilient means adapted to lie in one of the grooves and to co-operate with the other groove to firmly grip the hair, and means for locking the arms in closed position.

4. In a device for permanently waving hair, a clamp having opposed relatively movable arms, each provided with a groove, a rod pivotally supported and carrying resilient means adapted to lie in one of the grooves and to co-operate with the other groove to firmly grip the hair, means for locking the arms in closed position, a spindle co-operating with the clamp, and a double lock permitting rotation of the spindle only in one direction.

In testimony whereof I affix my signature.
HARRY BONAT.
